[57] CLAIM

The ornamental design for a telecommunications block test adapter, as shown and described.

DESCRIPTION

FIG. 1 shows a right side elevation view of a first embodiment of my new design with the left side elevation view being a mirror image thereof;

FIG. 2 shows a bottom plan view thereof;

FIG. 3 shows a top plan view thereof;

FIG. 4 shows a rear elevation view thereof;

FIG. 5 shows a front elevation view thereof;

FIG. 6 shows a right side elevational view of a second embodiment of my new design with the left side elevation view being a mirror image thereof;

FIG. 7 shows a bottom plan elevation view thereof;

FIG. 8 shows a top plan view thereof;

FIG. 9 shows a rear elevation view thereof;

FIG. 10 shows a front elevation view thereof;

FIG. 11 shows a right side elevation view of a third embodiment of my new design with the left side elevation view being a mirror image thereof;

FIG. 12 shows a bottom plan view thereof;

FIG. 13 shows a top plan view thereof;

FIG. 14 shows a rear elevation view thereof;

FIG. 15 shows a front elevation view thereof;

FIG. 16 shows a right side elevation view of a fourth embodiment of my new design with the left side elevation view being a mirror image thereof;

FIG. 17 shows a bottom plan view thereof;

FIG. 18 shows a top plan view thereof;

FIG. 19 shows a rear elevation view thereof; and,

FIG. 20 shows a front elevation view thereof.
